UNITED STATES PATENT OFFICE.

THOMAS J. McELHENIE, OF PHILADELPHIA, PENNSYLVANIA, ASSIGNOR TO THE OHIO VARNISH COMPANY, OF CLEVELAND, OHIO, A CORPORATION OF OHIO.

GRAINING-TOOL.

1,120,832.

Specification of Letters Patent.

Patented Dec. 15, 1914.

Application filed March 20, 1913. Serial No. 755,671.

To all whom it may concern:

Be it known that I, THOMAS J. McELHENIE, a citizen of the United States, residing at Philadelphia, in the county of Philadelphia and State of Pennsylvania, have invented a certain new and useful Improvement in Graining-Tools, of which the following is a full, clear, and exact description, reference being had to the accompanying drawings.

The object of this invention is to provide a useful comb for use by grainers in producing finishes in imitation of various woods. The comb is particularly designed for use on depressed surfaces, like the panels of doors, windows, moldings, etc., and may also be used in small grooves, corners and small curved surfaces, both depressed curves and convex surfaces, such as the rounded corners of window casings and quarter-round moldings. To provide for the proper treatment of such surfaces I have devised a peculiarly shaped body carrying a series of soft rubber combs of different fineness. On each side of this body is carried a flat block having combs on the edges of different shapes and length, adapted to fit into various surfaces, corners, and narrow grooves, and adapted to be brought out and clamped in an operative position with respect to the body to accommodate the particular surface which the workman wishes to comb. The shape of the body allows various comparatively inaccessible surfaces to be operated on, while these blocks on the sides may be so adjusted to reach still more inaccessible surfaces and of a greater variety of shapes. The different widths of teeth of the combs provide for producing imitations of different kinds of wood.

The invention is illustrated in the drawings hereof and is hereinafter more fully described and the essential characteristics set out in the claims.

In the drawings, Figure 1 is a view of the side of my comb, showing one of the blocks attached to the side in an operative position; Fig. 2 is a view of the other side showing the other block with one of the combs in an operative position, while the block shown in the first view is clamped in a position, out of the way, and does not show in this view; Fig. 3 is a longitudinal central sec-

tion of the tool showing the method of clamping the blocks to the body; Fig. 4 is a transverse section thereof taken on the line 4—4 of Fig. 3.

The body of the tool is designated 5. It may be wood or other suitable material. It is flat and has two side wings 6 and 7 and a comparatively long wing 8 at one end. These wings carry rubber graining combs, designated 10, 11 and 12 respectively. These combs 10, 11 and 12 are preferably considerably thinner than the body 5 and are held to these wings by seating in grooves therein, each comb snugly occupying its groove and being cemented, or otherwise secured into it. The pitch or distance between the teeth of the various combs is preferably different in each comb, to provide for various kinds of work.

It will be noted that each comb extends substantially the full width of the wing which carries it; that is to say, the ends of the combs are flush with the ends of the corresponding wings. This enables the comb to act clear up to the edge of any surface to which the wing can present it, and the wing, by extending from the body, can reach the various depressed surfaces. For example, the combs 10 and 11 may be used on any panel, a depression of which back of the tile is not greater than the projection of the wing and comb. I find that these projections may be made of sufficient length to accommodate all ordinary doors and molding, while allowing the whole tool to be in a convenient compass. For more depressed surfaces, the long wing 8 is provided, the comb on this wing being able to reach very deep molding, stairway spindles, etc., or used to reach under the railings on porches, for example.

The two blocks carried on each side of the body 8 form adjustable wings which may be used to reach many kinds of surfaces and corners. Each of these blocks 14 and 15 has L-shaped slots through their middle portion, designated respectively 17 and 18. Passing through these slots are bolts 20, each having a squared head 21 fitting into a slot 22 made through the middle portion of the body 8 and having an open end 23 through which these heads 21 may be passed. On each side of the grooves are thin metal

strips having their inner edges just far enough apart to admit the body of the bolt 20 and overhang the slot 22 to engage the head 21 of the bolt 20. The bolts 20 are 5 provided with washers 25 and thumb screws 26, and it will be seen that they may be moved to any position along the slot 20, and the block 14 and 15 clamped firmly in various positions and at any angle with the 10 body, or either block may be removed altogether, if desired. These block 14 and 15 are preferably made somewhat thinner than the body 8 and have combs, around their various-shaped edges, which are the equal in 15 width to the thickness of the block and may be secured thereto by cement, nails, or any suitable means. It will be seen from Figs. 1 and 2 that these block 14 and 15 may be clamped into position to correspond to any 20 of the wings 10, 11 and 12, while having a great variety of combs of different fineness and of different width, as well as being adapted to fit different shaped surfaces. For 25 example, the comb 26, in Fig. 1, might be used to comb wood which is intended to represent quarter-sawed oak, by drawing it across the wood, while holding it diagonally to the direction of movement. In such case the width of the teeth would produce rather 30 wide stripes, as desired. The small comb 27 on the corner near the one end of the comb 26 might be used in connection with the comb 26 to reach into a corner, for example. The comb 28, which is somewhat narrower 35 than the comb 26, might be used on a narrow panel for which the comb 26 would be too wide. It will be seen that either of the blocks 14 and 15 might be conveniently used 40 to grain surfaces, which were not flat or parallel with the other work being grained, by setting the block around at a suitable angle. The block 15 carries a curved comb 29, which is shown in position for operation in 45 Fig. 2, adapted to grain rounded corners or half-round moldings, for example. The small comb 30 might be used for many comparatively inaccessible corners and for molding having many small curves in its surface. The convex curved comb 32 might be used 50 for concaved surfaces, such as the fillet frequently used around the edges of the floor. The comb 34 is intended to be used for surfaces narrower than those which could be reached by the comb 28 and is conveniently 55 used on surfaces not flat or parallel with the rest of the work.

The tool described is very simple and cheap of construction and is convenient to hold in the hand, and I have found by actual 60 experience that it is very effective and convenient in use and provides for reaching surfaces of various characters which the grainer encounters about household wood-work and which have heretofore been difficult of treatment. By providing a comb of 65

this character which can conveniently reach these various surfaces, instead of having to rely on wiping out with the cloth, for example, I reduce the skill required in the treatment of such surfaces, and thus enable 70 an amateur to more easily perform the processes mentioned.

Having thus described my invention, what I claim is:

1. A graining comb comprising a flat 75 body having a wing projecting from its side and a second wing projecting from its end, the width of said wings being different, and graining combs carried by the respective wings and extending substantially the full 80 width thereof.

2. In a tool of the character described, a flat body having a wing projecting from a side and a wing of different dimensions projecting from one end, and graining combs 85 of different pitch carried by said wings respectively, said combs extending substantially the full length of the wings.

3. In a tool of the character described, a flat body having a graining comb on its 90 edges, and a flat block adjustably carried on one side of the body and having a graining comb on its edge.

4. In a tool of the character described, a flat body having wings projecting from 95 two sides, graining combs carried by said wings respectively, a block carried on each side of the flat body and having various shaped edges carrying graining combs on such edges and adapted to be brought into 100 operative position or moved to an inoperative position between the wings.

5. In a graining tool of the character described, a flat body having projecting wings, graining combs carried by these wings, a 105 flat block carried on each side of the flat body having various shaped edges, graining combs carried on these edges, and means for clamping each block in an operative or inoperative position.

6. A flat body, a graining comb carried by an edge thereof, said body having a slot in one of its flat sides, a block having a graining comb on its edge, and means slideable in 110 the slot for clamping the block in various 115 positions.

7. In a tool of the character described, a flat body having projecting wings, graining combs carried by said wings, a slot in the body having overhanging edges, a bolt having a head slideable in said slot, and a flat block having various shaped edges, graining combs carried on said edges, said blocks being adapted to be clamped by the bolt 120 in position to use any of the various combs 125 on its edges.

8. In a tool of the character described, a flat body having a slot therein, bolts having their heads adapted to slide in said slot, means at the sides of the slots for engaging 130

the heads of the bolt, flat blocks adjacent the sides of the flat block body and having slots therethrough adapted to fit over these bolts, means on the bolts for clamping these blocks 5 in various positions, and graining combs carried on the edges of the blocks.

In testimony whereof, I hereunto affix my signature in the presence of two witnesses.

THOMAS J. McELHENIE.
